UNITED STATES PATENT OFFICE.

FRANK V. TISCHER, OF DAYTON, OHIO, ASSIGNOR TO THE BOCEL COMPANY, OF DAYTON, OHIO, A CORPORATION OF OHIO.

METHOD OF MAKING LAMINATED STRUCTURES.

Application filed August 16, 1923. Serial No. 657,813.

To all whom it may concern:

Be it known that I, FRANK V. TISCHER, a citizen of the United States, residing at Dayton, in the county of Montgomery and 5 State of Ohio, have invented certain new and useful Improvements in Methods of Making Laminated Structures, of which the following is a specification, reference being had therein to the accompanying 10 drawing.

My invention relates to a new article of manufacture in laminated structures and method of making such an article of manufacture.

15 It is the object of my invention to provide a laminated structure of wood, leather, or cloth, or any similar substance in combination with a glue and coagulant.

It is a further object of my invention to 20 provide a method of manufacture of such articles which will result in a product that is strong, durable, and water resistant, which may be easily practiced, and in which the functions of the several elements employed will not interfere with one another.

Referring to the drawings:

Fig. 1 is a section of a piece of wood showing a coagulant applied;

Fig. 2 is a section of the wood with the 30 coagulant applied and also the glue and veneer in place;

Fig. 3 is a section showing the wood, coagulant, glue and organic substance such as leather.

35 Referring to the drawings in detail:

1 is a strip of wood. To this wood is applied a material known as a coagulant which is applied to the surface of the wood, as at 2, and allowed to soak into the wood as indicated in the shaded area 3.

As a coagulant I found a saturated solution of bicromate of potash satisfactory. I also used a solution of formaldehyde of 20% to 40% strength.

45 I do not desire to confine myself to these specific compounds as compounds having these characteristics other than the ones specified may be employed.

After applying the coagulant in liquid 50 form I allow it to dry, depending upon the nature of the coagulant and the nature of the wood, from two minutes to twelve hours, approximately. To determine how long it should dry it is necessary to be sure that the

coagulant thoroughly soaks into the surface 55 of the wood in order to prevent the coagulant from getting on the glue brush and making the glue insoluble therein.

After the coagulant dries I then apply a coat of glue 4 thereto and upon the glue 60 mount and veneer strip 5.

In the event that I desire to mount a veneer strip of leather rather than of wood, I apply the leather directly upon the glue as indicated by the leather strip 6 in Fig. 3. 65

It will be understood that if I desire to mount additional layers of veneer the same process is repeated.

It will also be understood that if I desire pressure may be applied to the veneer or 70 other substance mounted on the glue.

I do not desire to limit myself to the particular details as hereinbefore described, but comprehend within my invention a suitable modification thereof for its practice. 75

Having thus fully described my invention, what I claim as new and desire to secure by Letters Patent, is:—

1. In a method of joining articles to one another, providing a supporting body which 80 is relatively porous, permitting a coagulant to be absorbed and dried thereon and therein, applying a coating of glue, and applying a second body thereto.

2. In a method of joining articles to one another, providing a supporting body which 85 is relatively porous, permitting a coagulant to be absorbed and dried thereon and therein, applying a coating of glue, and applying a second body thereto, and applying pressure.

3. In a process of forming laminated structures, selecting a supporting body, applying a coagulant to the surface thereof, allowing it to be absorbed by a supporting 95 body, allowing the coagulant to dry, applying glue to the surface to which the coagulant has been applied, and applying a veneer to the glue.

4. In a process of forming laminated 100 structures, applying a coagulant to the surface of a supporting body, allowing it to dry, applying glue and applying the structure to be supported by the supporting body. 105

In testimony whereof, I affix my signature.

FRANK V. TISCHER.
